PULL GUN

George J. Van Hecke, Detroit, Mich., assignor to Huck Manufacturing Company, Detroit, Mich., a corporation of Michigan

Application February 3, 1956, Serial No. 563,284

18 Claims. (Cl. 218—47)

This invention relates to driving devices and, more particularly, to an improved fluid-actuated pull gun for driving blind rivets and the like.

An object of the present invention is to overcome disadvantages in prior fluid-actuated pull guns of the indicated character and to provide an improved fluid-actuated pull gun incorporating improved and simplified driving means.

Another object of the invention is to provide an improved pull gun incorporating improved means for reducing the clearance requirements between the end of the gun and the longitudinal axis of a blind rivet or the like during the driving thereof.

Another object of the invention is to provide an improved pull gun that is economical to manufacture and assemble, durable, efficient and reliable in operation.

Another object of the invention is to provide an improved fluid-actuated pull gun incorporating improved control means which facilitates the successive actuation of the driving components as a function of predetermined driving forces.

Still another object of the invention is to provide an improved fluid-actuated pull gun which is compact and relatively light in weight, which may be operated efficiently with a minimum of clearance in relatively close quarters, and which reduces the labor and expense of driving blind rivets and the like.

The above as well as other objects and advantages of the present invention will become apparent from the following description, the appended claims and the accompanying drawings wherein:

Figure 1 is a longitudinal sectional view of a fluid-actuated pull gun embodying the present invention;

Fig. 2 is a top plan view of the pull gun illustrated in Figure 1;

Fig. 3 is a transverse sectional view of the pull gun illustrated in Figure 1, taken on the line 3—3 thereof;

Fig. 4 is a sectional view of the pull gun illustrated in Figure 1, taken on the line 4—4 thereof;

Figs. 5A and 5B are longitudinal sectional views of a blind rivet before and after the driving operation; and

Figs. 6, 7, 8 and 9 are diagrammatic longitudinal sectional views showing successive steps in a rivet setting operation utilizing the pull gun embodying the present invention.

Referring to the drawings, the present invention is shown incorporated in a fluid-actuated pull gun, generally designated 5, which is of the double-acting type and which is particularly adapted for use in driving conventional conical keystone locking-type blind rivets, although it will be understood that the present invention is applicable to other uses. The pull gun 5 includes a housing 6 which defines a cylinder 7 in which is mounted a pneumatic piston assembly 8. The housing 6 also includes an integral neck portion 9, and an hydraulic driving head assembly 10 is mounted on the end of the neck portion 9 remote from the cylinder 7. The neck portion 9 serves as a hand grip and also carries an elongate cylin-

2

der 11 in which an hydraulic ram assembly 12 is reciprocally mounted. The cylinder 11 is filled with hydraulic fluid, and the hydraulic ram assembly serves to transmit fluid pressure imposed on the piston assembly 8 to the driving head assembly 10.

For the purpose of controlling the piston assembly 8, a trigger 14 is provided which is pivotally connected to the neck portion 9 of the housing at a position adjacent the head 10. The trigger 14 is operatively connected to 10 a valve 20 through the agency of a spring 16 and an actuating lever 18, and the valve 20 is slidably mounted in the bore 21 of a valve housing 22 fixed to the housing 6.

The valve housing 22 is provided with an inlet 31 15 which is connected by a supply line 32 to a source of air under pressure, while the bore 21 of the valve housing communicates with the head and rod ends of the cylinder 7 through ports 30 and 34, respectively.

As shown in Fig. 1, the diameter of the left end portion of the valve 20 is substantially greater than the diameter of the right end portion thereof. Because of the differences in the cross sectional areas of the opposite end portions of the valve, the valve tends to move to the left when air is admitted under pressure in the bore 25 21. Consequently, the valve moves to the position shown in Fig. 1 whenever the trigger 14 is released.

The piston assembly 8 includes a piston 24 which is mounted for reciprocation in the cylinder 7, and the piston 24 is connected by means of a drive tube 26 to a 30 piston 28 mounted for reciprocation in the cylinder 11. With such a construction, when the trigger 14 is squeezed, it acts through the spring 16 and the lever 18 to move the valve 20 to the right, as viewed in Figure 1, to connect the head end of the cylinder 7 to the source of air 35 pressure through the port 30, the bore 21 of the valve housing 22 and the supply line 32. At the same time, the rod end of the cylinder 7 is connected to atmosphere through the port 34. This action admits the air under pressure into the head end of the cylinder 7 and relieves 40 the pressure in the rod end of the cylinder 7, with the result that the piston 24 and the piston 28 are driven forwardly and apply pressure to the hydraulic fluid in the cylinder 11.

The driving head 10 of the gun includes a collet or 45 gripping jaw members 40 which serve to grip and pull a rivet pin during the driving thereof. The collet members 40 are mounted in one end of a tubular actuating shaft 42, the opposite end of which threadably engages a piston rod 44. In accordance with the present invention, the 50 piston rod 44 is secured to a piston 46 mounted for reciprocation in a cylinder 48, the longitudinal axis of the piston rod 44 being offset with respect to the longitudinal axes of the piston 46 and the cylinder 48 toward the end 49 of the gun. With such a construction, the distance 55 between the end 49 of the gun and the longitudinal axis of the piston rod 44 is reduced, thereby facilitating the use of the gun in relatively inaccessible locations where clearance requirements for the gun are critical.

Thrust bushing members 50 and 52 are fitted over the 60 piston rod 44 and the member 42 and support an inner anvil 54 in a fixed position relative to the driving head 10. An outer anvil 56 is provided which is mounted coaxially with respect to the inner anvil 54 and which is supported upon a tubular member 58 that extends into a secondary cylinder 62 provided within the head 10, the tubular member 58 being retained by an integral flange 60. The tubular member 58 bears against a secondary piston 64 65 that is mounted for reciprocation in the secondary cylinder 62, the fluid pressure applied to the secondary piston 64 being controlled, as will be explained in greater detail, to maintain the outer anvil 56 in an advanced position

beyond the inner anvil 54 until a predetermined pulling force is exerted on the rivet being driven.

The secondary cylinder 62 is filled with hydraulic fluid and is provided with a port 66 leading through a spring-biased valve 68 and a port 72 to a secondary reservoir 70. In addition, the secondary reservoir 70 is connected to the secondary cylinder 62 by a passageway 79 leading through a check valve 74 to an inlet port 76 in the secondary cylinder 62. The secondary reservoir 70 is substantially cylindrical in the embodiment of the invention illustrated and is provided with a freely slideable piston 78. An air supply line 100 is also provided which communicates with the upper end of the main hydraulic cylinder 48, and the upper end of the cylinder 48 communicates with the upper end of the reservoir 70 through a port 101.

The pull gun may be operated to drive a blind rivet assembly, generally designated 80, of the conical keystone lock type. As shown in Figs. 5A and 5B, rivets of the type illustrated include a pin 81 and a collar 82, the pin having an enlarged head portion 83 and a shank portion 84 while the collar includes a sleeve portion 85, a flange portion 86 and a frangible locking portion 87. The rivet assembly is initially inserted into aligned apertures 88 provided in the workpieces 89 and 90 which are to be fastened together. The gripping jaws of the collet 40 are then fitted over the pin 81 of the rivet assembly and the outer anvil 56 is pressed against the flange 86 of the rivet collar. The trigger 14 is then squeezed so as to move the valve 20 in the bore 21 of the valve housing 22 to open the port 30 to admit compressed air to the head end of the cylinder 7. At the same time, the port 34 is opened to atmosphere. The compressed air thus drives the piston 24 forwardly, and the piston 24 acts upon the ram piston 28 through the agency of the driving tube 26 to drive the hydraulic fluid in the ram cylinder 11 through the port 92 into the hydraulic cylinder 48. The hydraulic fluid thus forces the piston 46, together with the piston rod 44, upwardly, as viewed in Figure 1. The piston rod 44 then draws the collet actuating member 42 upwardly so that the collet 40 grips the rivet pin and pulls the rivet pin through the rivet collar. The reaction against the pulling force on the rivet pin 81 is borne by the outer anvil 56 which bears against the flange 86 of the collar. As the head 83 of the rivet pin is drawn against the sleeve portion 85 of the collar, the shank 84 of the rivet pin expands the sleeve portion 85 of the collar to fill the apertures 88 in the workpieces 89 and 90 and the end of the sleeve portion 85 adjacent the head 83 of the pin is upset to form the blind head 91 of the rivet. At this point, the piston rod meets with substantially increased pulling resistance, and the pressure of the hydraulic fluid within the cylinder 48 increases sufficiently to move the valve 68 against its biasing spring 71. This movement of the valve 68 opens the port 66 so that hydraulic fluid trapped within the secondary cylinder 62 can pass into the secondary reservoir 70. This permits the outer anvil 56 to retract in response to the reaction force against the pulling of the rivet pin and brings the inner anvil 54 into engagement with the collar of the rivet assembly. The inner anvil 54 bears against the frangible portion 87 provided on the rivet collar, and further movement of the piston 46 causes the inner anvil 54 to sever the frangible portion 87 from the collar and drive the severed portion between the collar and the pin to form the keystone lock, as will be appreciated by those skilled in the art. After the keystone lock has been completed, additional movement of the piston 46 breaks off the rivet pin at its break point 95. The broken-off end of the rivet pin is then ejected through the hollow piston rod 44 and a tube 49 which extends from the upper end of the piston rod and is slidably sealed through the head 98 of the hydraulic cylinder 48.

The trigger 14 is thereupon released and the control valve 20 is returned to its initial position because of the

differences in the cross sectional areas of the opposite end portions of the valve, as previously described. Movement of the control valve 20 to its initial position opens the port 30 to atmosphere and connects the port 34 to the source of air pressure so as to retract the piston 24. The rod end of the cylinder 7 is connected by the air tube 100 and the port 101 to the head ends of the hydraulic cylinder 48 and the reservoir 70 so that compressed air in the rod end of the cylinder 7 is transmitted through the tube 100 to the hydraulic cylinder 48 and through the port 101 to act on the piston 78 in the reservoir 70. Thus, air admitted through the port 34 to retract the piston 24 also forces the hydraulic piston 46 downwardly, as viewed in Fig. 1, into its initial positions, thereby forcing the hydraulic fluid in cylinder 48 through port 92 into cylinder 11. Similarly, the compressed air admitted through the port 101 into the upper end of the secondary reservoir 70 drives the secondary reservoir piston 78 downwardly to force the hydraulic fluid held therein through the check valve 74 and the port 76 into the secondary cylinder 62. The returning fluid forces the secondary piston 64 downwardly to drive the outer anvil 56 back to its advanced position preparatory to a repetitive operation of the gun.

An oil reservoir 102 may also be provided within the drive tube 26 of the hydraulic ram assembly 12. The reserve oil in the reservoir 102 may be pressurized by a piston 104 biased forwardly by a spring 105. The oil may be fed into the cylinder 11 through a valve 106 provided in the ram piston 28. Such a supply minimizes difficulties that might otherwise be encountered in the event of leakage of hydraulic fluid during operation of the gun.

In order that the gun may be filled conveniently with hydraulic fluid, suitable fittings, such as 110 and 114, may be provided.

The hydraulic pressure at which secondary movement takes place, i. e., at which the outer anvil 56 is retracted, may be varied by adjusting the biasing spring 71 of the valve 68 through the agency of a screw 69 in order to provide proper operation under varying conditions and with various types and sizes of rivets.

While a preferred embodiment of the invention has been shown and described, it will be understood that various changes and modifications may be made without departing from the spirit of the invention.

What is claimed is:

1. In a fluid-actuated pull gun, the combination comprising a body defining first and second cylinders, a pair of pistons, one of said pistons mounted for reciprocation in each of the cylinders defined by said body, rod means fixed to one of said pistons, the longitudinal axis of said rod means being offset with respect to the longitudinal axis of the first cylinder, means for successively establishing fluid circuits to the first cylinder at opposite ends of said one piston to drive said one piston in opposite directions, and means responsive to a predetermined fluid pressure in the first cylinder for permitting relative movement between said second piston means and said body.

2. In a fluid-actuated pull gun, the combination comprising a body defining first and second cylinders, a first piston mounted for reciprocation in the first cylinder defined by said body, a second piston mounted for reciprocation in the second cylinder defined by said body, means for successively establishing fluid circuits to the first cylinder at opposite ends of said first piston to drive said first piston in opposite directions, and means responsive to the fluid pressure in the first cylinder for establishing fluid circuits communicating with the second cylinder.

3. In a fluid-actuated pull gun, the combination comprising a body defining first and second cylinders, a first piston mounted for reciprocation in the first cylinder defined by said body, a rod fixed to said first piston, a

second piston mounted for reciprocation in the second cylinder defined by said body, the longitudinal axis of said rod being offset with respect to the longitudinal axis of the first cylinder, means for successively establishing fluid circuits to the first cylinder at opposite ends of said first piston to drive said first piston in opposite directions, and means responsive to the fluid pressure in the first cylinder for establishing fluid circuits communicating with the second cylinder.

4. In a fluid-actuated pull gun, the combination comprising a body defining first and second cylinders, a first piston mounted for reciprocation in the first cylinder defined by said body, a second piston mounted for reciprocation in the second cylinder defined by said body, the longitudinal axis of said first piston being offset with respect to the longitudinal axis of said second piston, means including valve means for successively establishing fluid circuits to the first cylinder at opposite ends of said first piston to drive said first piston in opposite directions, fluid reservoir means, and means responsive to the fluid pressure in the first cylinder for establishing a fluid path between the second cylinder and said reservoir.

5. In a fluid-actuated pull gun, the combination comprising a body defining first and second cylinders, a first piston mounted for reciprocation in the first cylinder defined by said body, a rod fixed to said first piston, a second piston mounted in the second cylinder for reciprocation relative to said rod, the longitudinal axis of said rod being offset with respect to the longitudinal axis of said first piston, means including valve means for successively establishing fluid circuits to the first cylinder at opposite ends of said first piston to drive said first piston in opposite directions, and means responsive to the fluid pressure in the first cylinder for controlling the fluid pressure in the second cylinder.

6. In a fluid-actuated pull gun, the combination comprising a body defining first and second cylinders, a first piston mounted for reciprocation in the first cylinder defined by said body, a rod fixed to said first piston, a second piston mounted in the second cylinder for reciprocation relative to said rod, the longitudinal axis of said rod being offset with respect to the longitudinal axis of said first piston, the longitudinal axis of said rod being aligned with the longitudinal axis of said second piston, means including valve means for successively establishing fluid circuits to the first cylinder at opposite ends of said first piston to drive said first piston in opposite directions, and means responsive to the fluid pressure in the first cylinder for controlling the fluid pressure in the second cylinder.

7. In a fluid-actuated pull gun, the combination including a body defining a pair of spaced cylinders, a first piston mounted for reciprocation in one of the cylinders defined by said body, a second piston mounted for reciprocation in the other cylinder, means including first valve means selectively operable to successively establish fluid circuits to the one cylinder at opposite ends of said first piston to drive said first piston in opposite directions, and means for controlling the movement of said second piston in the other cylinder as a function of the fluid pressure in the one cylinder.

8. In a fluid-actuated pull gun, the combination including a body defining a pair of spaced cylinders, a first piston mounted for reciprocation in one of the cylinders defined by said body, a piston rod fixed to said first piston, the longitudinal axis of said rod being offset with respect to the longitudinal axis of said first piston, a second piston mounted for reciprocation in the other cylinder, means including first valve means selectively operable to successively establish fluid circuits to the one cylinder at opposite ends of said first piston to drive said first piston in opposite directions, and means including second valve means responsive to the fluid pressure in

the one cylinder for controlling the fluid pressure and the movement of the second piston in the other cylinder.

9. In a fluid-actuated pull gun, the combination including a body defining a pair of spaced cylinders, a first piston mounted for reciprocation in one of the cylinders defined by said body, a piston rod fixed to said first piston, the longitudinal axis of said rod being offset with respect to the longitudinal axis of said first piston, a second piston mounted for reciprocation in the other cylinder, means including first valve means selectively operable to successively establish fluid circuits to the one cylinder at opposite ends of said first piston to drive said first piston in opposite directions, means including second valve means responsive to the fluid pressure in the one cylinder for controlling the fluid pressure and the movement of said second piston in the other cylinder, and driving means operatively connected to said pistons.

10. In a fluid-actuated pull gun, the combination comprising a body defining a pair of spaced cylinders, a first piston mounted for reciprocation in one of the cylinders defined by said body, a second piston mounted for reciprocation in the other cylinder, a first fluid reservoir, first fluid circuit means connecting said first fluid reservoir with the one cylinder defined by said body, a second fluid reservoir, second fluid circuit means connecting said second reservoir with the other of said cylinders, selectively operable control means for controlling the flow of fluid through said first circuit means, and means responsive to the fluid pressure in the first cylinder for controlling the flow of fluid through said second circuit means.

11. In a fluid-actuated pull gun, the combination comprising a pair of longitudinally spaced cylinders, a first piston mounted for reciprocation in one of the cylinders defined by said body, a rod fixed to said first piston with the longitudinal axis thereof offset with respect to the longitudinal axis of said first piston, a second piston mounted in the other cylinder for movement relative to said rod, means for forcing fluid under pressure into the one cylinder, means responsive to the fluid pressure in the one cylinder for controlling the fluid pressure in the other cylinder, and successively actuatable driving means operatively connected to said pistons.

12. In a fluid-actuated pull gun, the combination comprising a housing defining a bore, first piston means mounted for reciprocation in the bore defined by said housing, a body defining a pair of longitudinally spaced cylinders, second piston means mounted for reciprocation in one of the cylinders defined by said body, third piston means mounted for reciprocation in the other cylinder defined by said body, means including first valve means selectively operable to actuate said first piston means to force fluid under pressure into the one cylinder, and means including second valve means responsive to the fluid pressure in the one cylinder for controlling the fluid pressure in the other cylinder.

13. In a fluid-actuated pull gun, the combination comprising a housing defining a bore, first piston means mounted for reciprocation in the bore defined by said housing, a body defining a pair of longitudinally spaced cylinders, second piston means mounted for reciprocation in one of the cylinders defined by said body, a rod fixed to said second piston means with the longitudinal axis thereof offset with respect to the longitudinal axis of said second piston means, third piston means mounted in the other cylinder defined by said body for movement relative to said rod, means including first valve means selectively operable to actuate said first piston means to force fluid under pressure into the one cylinder, means including second valve means responsive to the fluid pressure in the one cylinder for controlling the fluid pressure in the other cylinder, and driving means operatively connected to said second and third piston means.

14. In a fluid-actuated pull gun, the combination comprising a housing defining a bore, a first piston mounted

for reciprocation in the bore defined by said housing, a body defining a pair of longitudinally spaced cylinders, a second piston mounted for reciprocation in one of the cylinders defined by said body, a rod fixed to said second piston with the longitudinal axis thereof offset with respect to the longitudinal axis of said second piston, a third piston mounted in the other cylinder defined by said body for movement relative to said rod, means including first valve means selectively operable to actuate said first piston to force fluid under pressure into the one cylinder, means including second valve means responsive to the fluid pressure in the one cylinder for controlling the fluid pressure in the other cylinder, and driving means operatively connected to said second and third pistons.

15. In a fluid actuated pull gun, the combination comprising a body defining a cylinder having first and second sections, a first piston mounted for reciprocation in the first section of the cylinder defined by said body, a second piston mounted for reciprocation in the second section of the cylinder defined by said body, means for successively establishing fluid circuits to the first section of the cylinder at opposite ends of said first piston to drive said first piston in opposite directions, and means responsive to the fluid pressure in the first section of the cylinder for establishing fluid circuits communicating with the second section of the cylinder.

16. In a fluid actuated pull gun, the combination comprising a body defining a cylinder having first and second sections, a pair of pistons, one of said pistons mounted for reciprocation in each of the sections of the cylinder defined by said body, rod means fixed to one of said pistons, the longitudinal axis of said rod means being offset with respect to the longitudinal axis of the first section of the cylinder, means for successively establishing fluid circuits to the first section of the cylinder at opposite ends of said one piston to drive said one piston in opposite directions, and means responsive to a predetermined fluid pressure in the first section of the cylinder for permitting relative movement between said second piston means and said body.

17. In a fluid actuated pull gun, the combination including a body defining a cylinder having first and second sections, a first piston mounted for reciprocation in the first section of the cylinder defined by said body, a second piston mounted for reciprocation in the second section of the cylinder defined by said body, a first fluid reservoir, first fluid circuit means connecting said first fluid reservoir with the first section of the cylinder defined by said body, a second fluid reservoir, second fluid circuit means connecting said second reservoir with the second section of the cylinder defined by said body, selectively operable control means for controlling the flow of fluid through said first circuit means, and means responsive to the fluid pressure in the first section of the cylinder defined by said body for controlling the flow of fluid through said second circuit means.

18. In a fluid actuated pull gun, the combination comprising a housing defining a bore, first piston means mounted for reciprocation in the bore defined by said housing, a body defining a cylinder having a pair of sections, second piston means mounted for reciprocation in one section of the cylinder defined by said body, third piston means mounted for reciprocation in the other section of the cylinder defined by said body, means including first valve means selectively operable to actuate said first piston means to force fluid under pressure into the one section of the cylinder, and means including second valve means responsive to the fluid pressure in the one section of the cylinder for controlling the fluid pressure in the other section of the cylinder.
